United States Patent Office

Des. 190,874
Patented July 11, 1961

190,874

CLOCK

Irene O. Kursh, 340 Melville, Palo Alto, Calif., and Jerry Cumbus, 110 3rd St., Sausalito, Calif.

Filed Aug. 8, 1960, Ser. No. 61,656

Term of patent 14 years

(Cl. D42—7)

FIG. 1 is a front perspective of a clock embodying our new design.

FIG. 2 is a rear perspective of the clock shown in FIG. 1.

FIG. 3 is a side elevational view of the clock shown in FIGS. 1 and 2.

We claim:

The ornamental design for a clock, substantially as shown.
